COUNTER

Edward M. Stolarz, 30 W. 60th St., New York, N.Y.

Filed June 17, 1963, Ser. No. 75,367

Term of patent 14 years

(Cl. D52—4)

FIG. 1

FIG. 2

FIG. 3

FIG. 4

FIG. 5

FIG. 6

FIG. 7

FIGURE 1 is a perspective view of a counter, showing my new design;

FIGURES 2 and 3 are perspective views of a second and third embodiment of the counter shown in FIGURE 1 and in FIGURES 4 to 7, inclusive, and differing from said embodiment in the base members and in proportions, the embodiment of FIGURE 3 differing further in having a shaft for mechanical drive shown in phantom line;

FIGURE 4 is a top plan view of the counter shown in FIGURE 1, the bottom thereof being a substantially planar surface;

FIGURE 5 is a side elevational view of the counter shown in FIGURE 1, the opposite side being a mirror image of the side shown;

FIGURE 6 is an end elevation of the counter shown in FIGURE 1, taken from the right of said figure; and

FIGURE 7 is an enlarged fragmentary cross section taken on the line 7-7 of FIGURE 4.

The essential features of my design reside in the por-

tions shown in full lines, said portions being characterized by the generally frustopyramidal housing member having cut-out areas on each end thereof and by the double-outlined viewing window provided by the top plan surface thereof.

I claim:

The ornamental design for a counter, as shown and described.
